US0D1101932S

(12) **United States Design Patent** (10) **Patent No.:** **US D1,101,932 S**
(45) **Date of Patent:** **** Nov. 11, 2025**

(54) **FRAME**

(71) Applicant: **DCSTAR INC.**, New York, NY (US)

(72) Inventor: **Ligui He**, New York, NY (US)

(**) Term: **15 Years**

(21) Appl. No.: **29/960,560**

(22) Filed: **Aug. 30, 2024**

Related U.S. Application Data

(63) Continuation of application No. 29/906,358, filed on Nov. 3, 2023, now Pat. No. Des. 1,048,375.

(57) **CLAIM**

The ornamental design for a frame, as shown and described.

DESCRIPTION

FIG. 1 is a left side view of a frame showing my new design;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is a perspective view thereof; and,

FIG. 8 is another perspective view thereof.

The dash-dash broken lines depict portions of the frame that form no part of the claimed design.

The dot-dash-dot broken lines define the bounds of the claimed design and form no part thereof.

The use of the symbol on the design article forming no part of the claimed design is a trademark published for opposition of DCSTAR INC.

1 Claim, 8 Drawing Sheets
